(57) **CLAIM**

The ornamental design for a support, as shown and described.

DESCRIPTION

In a preferred embodiment, the nature of this product is as a support for a plumbing fixture, such as a table base for a lavatory.

FIG. 1 is a right, top, front perspective view of a support embodying my new design;

FIG. 2 front elevational view thereof;

FIG. 3 is a right side elevational view thereof, the left side elevational view thereof being a mirror image of the right side shown;

FIG. 4 is a top plan view thereof;

FIG. 5 is a bottom plan view thereof; and,

FIG. 6 is a rear elevational view thereof.

The broken line representations of lavatory environment in FIG. 1, feet structure in FIGS. 2, 3 and 6, and tab structure in FIGS. 3-6 are for the purpose of illustration only, and form no part of the claimed design.
